DESIGN FOR A GAME UNIT OR SIMILAR ARTICLE

Erwin S. Lowe, New York, N. Y.

Application December 10, 1943, Serial No. 111,980

Term of patent 7 years

(Cl. D34—5)

To all whom it may concern:

Be it known that Erwin S. Lowe, a citizen of the United States and resident of the Borough of Manhattan, city, county, and State of New York, has invented a new, original, and ornamental Design for a Game Unit or Similar Article, of which the following is a specification, reference being had to the accompanying drawing, forming part thereof, in which

Fig. 1 is an exploded perspective view of the game unit embodying my new design; and

Fig. 2 is an enlarged plan view of the spinner board shown in Fig. 1.

I claim:

The ornamental design for a game unit or similar article, substantially as shown.

ERWIN S. LOWE.
